(57) **CLAIM**

The ornamental design for a heated apparel controller, as shown and described.

DESCRIPTION

FIG. 1 is a front perspective view of a heated apparel controller, showing my new design;

FIG. 2 is a front elevational view thereof;

FIG. 3 is a rear elevational view thereof;

FIG. 4 is a left side view thereof;

FIG. 5 is a top plan view thereof; and,

FIG. 6 is a bottom plan view thereof.

The broken lines in the figures are for the purposes of illustrating portions of the heated apparel controller, which form no part of the claimed design.

The dash-dot-dash broken lines define the bounds of the claimed design and form no part thereof.
